UNITED STATES PATENT OFFICE.

ERIC R. LUNDIUS, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,330,201.

Specification of Letters Patent. Patented Feb. 10, 1920.

Application filed February 28, 1918. Serial No. 219,602.

To all whom it may concern:

Be it known that I, ERIC R. LUNDIUS, a citizen of the United States, residing at Brooklyn, in the county of Kings, State of New York, have invented certain new and useful Improvements in Telephone-Exchange Systems, of which the following is a full, clear, concise, and exact description.

This invention relates to telephone exchange systems, and more particularly to such systems of the central energy type in which trunk circuits are employed in completing connections between telephone lines terminating at different switchboards.

An object of this invention is the provision of improved signaling means for such systems.

In accordance with a feature of this invention, apparatus, provided in a trunk circuit extending from a "B" to a desk operator's position, functions when the desk operator answers, to prevent the application to the trunk circuit of ringing current from a connected automatic ringing trunk circuit when the "A" operator subsequently connects with the outgoing end of the automatic ringing trunk circuit.

In accordance with another feature of this invention, the connected trunk circuits are provided with apparatus by means of which the desk operator may signal the "A" operator over the connected trunk circuits.

For a more complete understanding of this invention, reference should be had to the following description considered in connection with the accompanying drawings, in which Figures 1 and 2, when placed end to end, illustrate one embodiment thereof, and Figs. 1 and 3, when placed end to end, illustrate another embodiment thereof.

As shown in Fig. 1, a telephone line A, terminating at an "A" operator's position, is suitably connected with a link circuit B, which coöperates with an automatic ringing trunk circuit C to extend the line to a "B" operator's position. This trunk circuit C may be connected with another trunk circuit D (see Fig. 2), to extend the line to a desk operator's position. The trunk circuit D is jack-ended at the desk operator's position, at which is provided a cord circuit E, by means of which the desk operator may

answer a call incoming over the connected link circuit B and trunk circuits C and D from the telephone line A. The automatic 55 ringing trunk circuit C may connect with a trunk circuit F (see Fig. 3), which at the desk operator's position terminates in a switch or key by means of which the desk operator may answer incoming calls. The 60 apparatus shown to the left of the dotted line 4—4 is associated with the "A" operator's position, that shown between the dotted lines 4—4 and 5—5, with the "B" operator's position, and that shown to the 65 right of the dotted line 5—5, with the desk operator's position.

Subscriber "A" having initiated a call in the usual manner, and the link circuit B having been connected therewith in any desired manner, the "A" operator may actuate listening key 6 to connect the operator's telephone set therewith. Upon being advised that subscriber "A" desires to be connected with a line terminating at another 75 switchboard, the "A" operator restores the listening key 6 to normal position and communicates over an order wire circuit (not shown) with the "B" operator of the second switchboard and receives the trunk assignment. 80

Assuming trunk circuit C to be that assigned, the "A" operator inserts plug 7 of the link circuit B into jack 8 of the trunk circuit C, whereupon calling supervisory 85 lamp 9 is lighted over a circuit from battery through the lamp 9, resistance 10, sleeve contacts of the plug 7 and the jack 8 and resistance 11 to ground. Trunk relay 12 is also operated over a circuit from battery through the winding of calling supervisory relay 13, ring contacts of the plug 7 and the jack 8, right-hand winding of the trunk relay 12 and tip contacts of the jack 8 and the plug 7 to ground. The calling 95 supervisory relay 13 does not now operate, due to the high resistance of the right-hand winding of the trunk relay 12. If the "B" operator has not inserted plug 14 into a jack of another circuit, the operation of the 100 trunk relay 12 causes lamp 15 to be lighted over a circuit from battery through the lamp 15, contact of trunk relay 12, lower normal contact of relay 16 and resistance 17

to ground. The lighting of the lamp 15 indicates to the "B" operator that connection has been made with the assigned trunk circuit.

- 5 The "B" operator may now connect the plug 14 with the jack of the wanted line. However, if the number of the wanted line has been changed or if the wanted line is to receive some unusual service, the "B" operator will find in the multiple jack of the line called, a designation plug, which indicates that all calls for that line are to be referred to the information operator. In such a case, the "B" operator inserts the plug 14 into the 15 jack of a trunk circuit extending to the desk or switchboard of an information operator, for example, into jack 20 of the trunk circuit D (see Fig. 2). Relays 16 and 21 are thereupon operated over a circuit from battery through the lamp 15, winding of relay 16, sleeve contacts of the plug 14 and the jack 20, right-hand winding of relay 21 and contact 19 of slow operating relay 22 to ground. Relay 16, in operating, opens its 20 normal and closes its alternate contacts, whereupon ringing relay 23 operates over a circuit from battery through the winding of ringing relay 23, normal contact of relay 24, contact of trip relay 25, lower alternate contact of relay 16, contact of trunk relay 12, winding of relay 16, sleeve contacts of the plug 14 and the jack 20, right-hand winding of relay 21 and contact 19 of relay 22 to ground. The operation of ringing relay 23 25 connects a source of ringing current 26 through winding of trip relay 25 to the trunk circuit D. The winding of ringing relay 23, which is of comparatively low resistance, is now connected in parallel with the lamp 15, thereby extinguishing the lamp. The operation of relay 21 causes lamp 27, located at the information operator's desk, to be lighted over a circuit from battery through the lamp 27, left-hand normal contact of relay 28 and the contact of relay 21 30 to ground.

The information operator, observing the lighted condition of the lamp 27, inserts plug 30 into jack 31 of the trunk circuit D, whereupon relay 32 operates and lamp 33 lights over a circuit from battery through lamp 33, resistance 34, sleeve contacts of the plug 30 and the jack 31, lower winding of relay 32 and contact 35 of relay 22 to ground. Relay 32, in operating, bridges relay 36 across the tip and ring strands of the trunk circuit D. Relay 36 is immediately traversed by ringing current and operates. Trip relay 25 also operates, removing a short circuit from about the relay 24, which immediately operates, locks up, and short-circuits ringing relay 23. Ringing relay 23 thereupon releases, disconnecting ringing current from the trunk circuit D. Supervisory relay 37 45 then operates to include the left-hand wind-

ing of trunk relay 12 in parallel with the right-hand winding thereof, thereby reducing the resistance in circuit with the supervisory relay 13. Supervisory relay 13 thereupon operates to establish a shunt circuit, 50 including resistance 38, for the lamp 9, which is thereby effaced. The operation of relay 32 already referred to, also causes the energization of relay 28 over a circuit from battery through the winding and right-hand 55 normal contact of relay 28, lower contact of relay 32 and the contact of relay 21 to ground. Relay 28, upon being energized, opens the circuit of, and extinguishes lamp 27, and establishes a locking circuit for itself 60 through its left-hand alternate contact and contact of relay 21 to ground. Relays 28 and 36 being energized, relay 22 operates over a circuit from battery through the contact of relay 36, the winding of relay 22, the 65 right-hand contact of relay 28, the lower contact of relay 32 and the contact of relay 21 to ground. Relay 22, in operating, closes through the talking circuit to the information operator's desk. The opening of contact 19 of relay 22 removes a short circuit from resistance 39, which is thereupon included in the sleeve circuit of the plug 14 and the jack 20 for a purpose which will more fully hereinafter appear. The opening of contact 35 of relay 22 removes a short circuit from the upper winding of relay 32, whereupon this winding is included in circuit with the lamp 33, which is thereby extinguished. The sequence of operation of the relays described, following the insertion of the plug 30 into the jack 31, is such that ringing current is disconnected from the trunk circuit D, and direct current substituted therefor before the talking circuit is completed 100 through to the information desk, so that, if the information operator has listening key 40 actuated when plugging in, the usual disagreeable clicks attending the tripping of ringing current from an automatic ringing 105 circuit, are not produced in the information operator's receiver. After the listening key 40 is actuated the information operator may converse with the calling subscriber "A" and furnish the desired information. 110

Should the information operator, after conversing with subscriber "A", desire to communicate with the "A" operator to give instructions regarding the connection with the desired line, the information operator 115 may, by repeatedly actuating a key 45, cause the intermittent lighting of the calling supervisory lamp 9. The actuation of the key 45 short-circuits the windings of relay 32, which thereupon releases, disconnecting 120 the relay 36 from the tip and ring strands of the trunk circuit D. Supervisory relay 37 thereupon releases its armature, thereby increasing the resistance in circuit with the supervisory relay 13. Supervisory relay 13 125

then releases its armature, removing the shunt from the calling supervisory lamp 9, which thereupon lights. The lamp 33 is also lighted upon the actuation of the key 45. Upon the disconnection of the relay 36 from the trunk circuit D, this relay releases its armature, causing the deenergization of relay 22, which opens the talking circuit and in closing its upper and lower contacts, short-circuits the two condensers in the talking circuit, whereupon the condensers are discharged. Upon the restoration of the key 45 to normal position, relay 32 first operates, then relay 36 and then relay 22. Also upon the energization of relay 36, supervisory relays 37 and 13 operate to efface calling supervisory lamp 9. The lamp 33 is effaced immediately upon the restoration of the key 45 to normal position. The short-circuiting of the condensers each time relay 22 releases, serves to reduce the clicks resulting from the opening and closing of the talking circuit.

Should the "A" operator, after the "B" operator has connected the trunk circuit C with the trunk circuit D, and the information operator has connected the cord circuit E with the trunk circuit D, attempt to re-ring by withdrawing the plug 7 from and reinserting it into the jack 8, ringing current will not be connected with the trunk circuit D. The withdrawal of the plug 7 from the jack 8 releases the trunk relay 12, whereby the locking circuit of the relay 24 is opened. The reinsertion of the plug 7 into the jack 8 causes the energization of trunk relay 12, whereupon a circuit is established for the ringing relay 23, but since resistance 39 is now included in this circuit, ringing relay 23 does not receive sufficient current to cause it to move its armatures. In this manner, the apparatus functions to prevent the connection of ringing current with the trunk circuit D, if the trunk circuit C and the cord circuit E are already connected therewith when the cord circuit B is connected with the trunk circuit C. Therefore, if the information operator's telephone set should be connected with the talking circuit when the "A" operator connects with the trunk circuit, the inability to connect ringing current to trunk circuit D, prevents the production of very severe and disagreeable clicks in the receiver of the information operator.

The form of trunk circuit shown in Fig. 3 may be employed between the "B" board and the information operator's desk instead of the trunk circuit and cord circuit of Fig. 2. When so used, the insertion of the plug 14 of trunk circuit C into jack 50 of the trunk circuit F causes the operation of relay 51 over a circuit from battery through the lamp 15, winding of relay 16, sleeve contacts of the plug 14 and the jack 50, left-

hand normal contact of relay 52 and left-hand winding of relay 51 to ground. Relay 51, in operating, causes lamp 53 to be lighted over a circuit from battery through the right-hand contact of relay 51, right-hand contact of relay 52 and the lamp 53 to ground. The relays 16 and 23 of the trunk circuit C operate as before described.

The information operator, observing the lighted condition of the lamp 53, actuates listening key 54, thereby bridging relay 55 across the tip and ring strands of the trunk circuit F in parallel with the condenser 56 and in series with the right-hand winding of relay 51. Trip relay 25 and relay 55 thereupon operate. The operation of trip relay 25 causes the disconnection of the ringing current as before described, and the operation of relay 55 causes the energization of slow-operating relay 57 to connect the information operator's telephone set with the trunk circuit F. The actuation of the listening key 54 also causes the operation of relays 52 and 58, the former over a circuit from battery through the right-hand winding of relay 52 and contact 59 of listening key 54 to ground, and the latter over a circuit from battery through the left-hand contact of relay 51, winding of relay 58 and contact 59 of listening key 54 to ground. Relay 52, in operating, disconnects the left-hand winding of relay 51 from the sleeve circuit and includes its own left-hand winding in this sleeve circuit, thereby establishing a locking circuit for itself, and opens its right-hand contact, extinguishing the lamp 53. Relay 58, in operating, establishes a locking circuit for itself through its alternate contact and opens its normal contact, thereby removing a short circuit of resistance 60, which is thereby included in the sleeve and locking circuit of relay 52. The purpose of connecting resistance 60 in the sleeve circuit of the trunk circuit F is to prevent the connection of ringing current to the trunk circuit F, should the "A" operator attempt to re-ring as before described. While listening key 54 is actuated, relay 51 is energized in series with relay 55, and supervisory relays 37 and 13 are energized while the calling supervisory lamp 9 is effaced. Upon restoration of the listening key 54 to normal position, relays 13, 37, 51, 55, 57 and 58 release.

What is claimed is:

1. A telephone exchange system comprising a trunk circuit extending from a first to a second switchboard, a connecting circuit at the first switchboard connected with the trunk circuit, a source of ringing current thereat, a ringing relay in the connecting circuit adapted when operated to connect the source of ringing current with the trunk circuit, a normally open operating circuit for the ringing relay, means for closing

the operating circuit, a link circuit at the second switchboard, and means responsive to the connection of the link circuit with the trunk circuit for increasing the resistance of the operating circuit, thereby to prevent the operation of the ringing relay.

2. A telephone exchange system comprising a trunk circuit extending from a first to a second switchboard, a connecting circuit at the first switchboard connected with the trunk circuit, a source of ringing current thereat, a ringing relay in the connecting circuit adapted when operated to connect the source of ringing current with the trunk circuit, a normally open operating circuit for the ringing relay, means for closing the operating circuit, a link circuit at the second switchboard, and means responsive to the connection of the link circuit with the trunk circuit for rendering the operating circuit ineffective when subsequently closed by said first mentioned means.

3. A telephone exchange system comprising a trunk circuit extending from a first to a second switchboard, a connecting circuit at the first switchboard connected with the trunk circuit, a source of ringing current thereat, a ringing relay in the connecting circuit adapted when operated to connect the source of ringing current with the trunk circuit, a normally open operating circuit for the ringing relay, means for closing the operating circuit, a link circuit at the second switchboard, a resistance coil, and means responsive to the connection of the link circuit with the trunk circuit for including the resistance coil in the operating circuit, thereby to prevent the operation of the ringing relay.

4. A telephone exchange system comprising a trunk circuit extending from a first to a second switchboard, a connecting circuit at the first switchboard connected with the trunk circuit, a source of ringing current thereat, a ringing relay in the connecting circuit adapted when operated to connect the source of ringing current with the trunk circuit, a normally open operating circuit for the ringing relay, means for closing the operating circuit, a link circuit at the second switchboard, a resistance coil, a short circuit therefor normally included in the operating circuit, and an electromagnetic relay responsive to the connection of the link circuit with the trunk circuit for opening the short circuit and including the resistance in the operating circuit, thereby to prevent the operation of the ringing relay.

5. A telephone exchange system comprising a trunk circuit extending from a first to a second switchboard, a trunk circuit having normally open talking strands connected with the first trunk circuit at the second switchboard and extending therefrom

to a third switchboard, a link circuit at the first switchboard, a signaling device for the link circuit operating upon the connection thereof with the first trunk circuit, a link circuit at the third switchboard, an electromagnetic relay responsive to the connection of the second link circuit with the second trunk circuit for closing the normally open talking strands thereof, means responsive to the closure of the talking strands for stopping the operation of the signaling device, and an operator controlled switch at the third switchboard for causing the successive deenergization and energization of the electromagnetic relay whereby the signaling device is intermittently operated.

6. A telephone exchange system comprising a trunk circuit extending from a first to a second switchboard, a trunk circuit having normally open talking strands connected with the first trunk circuit at the second switchboard and extending therefrom to a third switchboard, a link circuit at the first switchboard, a signaling device for the link circuit operating upon the connection thereof with the first trunk circuit, a link circuit at the third switchboard, an electromagnetic relay responsive to the connection of the second link circuit with the second trunk circuit for closing the normally open talking strands thereof, a resistance coil connected across the talking circuit upon the response of the electromagnetic relay, a signal control relay in the first link circuit responsive to the connection of the resistance coil across the talking circuit to stop the operation of the signaling device, and an operator-controlled switch at the third switchboard for causing the successive deenergization and energization of the electromagnetic relay whereby the signaling device is intermittently operated.

7. A telephone exchange system comprising a trunk circuit extending from a first to a second switchboard, a trunk circuit having normally open talking strands connected with the first trunk circuit at the second switchboard and extending therefrom to a third switchboard, a link circuit at the first switchboard, a signaling device for the link circuit operating upon the connection thereof with the first trunk circuit, a link circuit at the third switchboard, an electromagnetic relay responsive to the connection of the second link circuit with the second trunk circuit for closing the normally open talking strands thereof, a resistance coil connected across the talking circuit upon the response of the electromagnetic relay, a signal control relay in the first link circuit controlled over the connected trunk circuit, a relay in the first trunk circuit energized upon the connection of the resistance coil across the second trunk circuit to de-

crease the resistance in circuit with the signal-control relay whereby the signal-control relay is energized to stop the operation of the signaling device, and an operator-controlled switch at the third switchboard for causing the successive deenergization and energization of the electromagnetic relay

whereby the signaling device is intermittently operated.

In witness whereof, I hereunto subscribe my name this 18th day of February A. D., 1918.

ERIC R. LUNDIUS.
